UNITED STATES PATENT OFFICE.

LOUIS F. VOISARD, OF GALION, OHIO, ASSIGNOR TO THE PLYMOUTH STAMPED METAL COMPANY, OF GALION, OHIO, A CORPORATION OF OHIO.

MACHINE FOR MAKING SHOE-TREES.

Application filed June 20, 1923. Serial No. 646,697.

To all whom it may concern:

Be it known that I, LOUIS F. VOISARD, a citizen of the United States, resident of Galion, county of Crawford, and State of Ohio, have invented new and useful Improvements in Machines for Making Shoe-Trees, of which the following is a specification, the principle of the invention being herein explained and the best mode in which I have contemplated applying that principle, so as to distinguish it from other inventions.

My invention relates to machines for making shoe-trees and particularly to apparatus of this character designed automatically to assemble the usual toe and heel forms of these trees with the intermediate flexible connector or body portion of the shoe-tree. Also, the invention relates to machines of this character in which specific nailing mechanism is provided for rigidly fastening the flexible connector to the forms, irrespective of the particular means by which the forms and connector are initially assembled. Improvements are also shown and claimed for new clamping mechanism designed temporarily rigidly to hold the flexible connector while the wooden forms are forced thereon.

The annexed drawings and the following description set forth in detail certain means embodying my invention, such means constituting, however, but one of the various forms in which the principle of the invention may be applied.

In said annexed drawings:

Figure 1 represents a fragmentary plan view, showing particularly the top of a working table and the arrangement of mechanism thereon.

Figure 1^a represents a fragmentary vertical section, upon an enlarged scale, taken in the plane indicated by the line I^a—I^a, Fig. 1.

Figure 2 is a front elevation of the machine.

Figures 3 and 4, represent, respectively, a plan view and a side elevation of the driving mechanism.

Figure 5 is a fragmentary vertical section, upon an enlarged scale, showing the starting position of certain cams designed to clamp the steel connector rigidly in place previous-

ly to the movement of the wooden forms toward and onto the ends of said connector. 55

Figure 6 is a fragmentary side elevation, upon an enlarged scale, showing the starting position of certain cams whose function is to force the wooden forms onto the ends of the flexible connector; and 60

Figure 7 is a fragmentary vertical section, upon an enlarged scale, of certain cams adapted to effect the nailing of the forms to the intermediate connector.

Referring to the annexed drawings in which the same parts are indicated by the same respective ordinals in the several views, I indicate a supporting frame by the ordinal 1 having a work table 2. A motor 3 is suitably supported in the frame 1 and is adapted to rotate a pulley 4 secured to a shaft 5 which through intermediate gearing 6 is adapted continuously to rotate a main driving shaft 7 which, through the medium of a clutch 8 controlled by a foot-treadle 9 and a treadle rod 10, can be coupled, as desired, to a cam shaft 11. 75

The design of the machine is to assemble certain shoe-tree forms, illustrated by the toe-form 24 and the heel-form 25, and a body portion or flexible intermediate steel band or connector 23, the same being automatically effected through the proper functioning of certain cams secured to the cam shaft 11, the operation including the initial clamping of the steel band 23 so that the assembling can be accomplished by forcing the forms 24 and 25 onto the ends of the band 23. The invention also includes further the rigid fastening of the forms 24 and 25 to the band 23 by means of automatically forcing nails 47 through holes 48 in the band 23, after the latter has been assembled in the forms 24 and 25, irrespective of the particular method or means by which the initial assembling of the forms 24 and 25 and the band 23 has been effected. 90

First, the wooden pieces or forms 24 and 25 are inserted by hand in suitable containers 36 and the band 23 is inserted by hand in a wedge-shaped groove 52 formed in the top of the two cooperating separable halves of an auxiliary table 27 mounted upon the main table 2. The exact position of the band 23 is determined by a spring-mounted guide pin 26 mounted in the table 2 and whose 100

protruding end is substantially of the same length as the proper length of one extending end 23' of the steel band 23 to insure the correct position of the latter relative to the operating elements of the machine. The cam shaft 11 then being thrown into action through the medium of the clutch 8, a pair of cams 12 act upon rollers 13 mounted between the arms 15 of yokes 14 having heads 16 to which are secured pins 17 adapted to reciprocate within horizontal recesses 18 in the table 2, all to force clamping blocks 21 secured to said pins 17 against the ends of the steel band 23 rigidly to hold the same, collars 19 being secured to the pins 17 at a spaced distance from the table 2 in the initial position of the cams 12, another pair of collars 20 loosely encircling the pins 17 and guiding the same adjacent the clamping blocks 21, so that coil-springs 22 are compressed between the collars 19 and 20, as the pins 17 and clamping blocks 21 move inwardly to hold the band 23. Next, a second pair of cams 29 act upon rollers 30 secured to rock-levers 31 suitably pivotally-mounted, to the other end of which levers 31 are secured rollers 32 disposed adjacent to heads 33 upon pins 34 secured in and projecting from blocks 35 disposed adjacent to the receiving members 36 for the forms 24 and 25. The blocks 35 and the members 36 are slidably mounted in the table 2, so that it is evident that the effect of the rotation of the cams 29 will be to force the forms 24 and 25 against and onto the ends of the steel band 23 and cause said ends to be inserted in said forms. Coil-springs 49 are contained within suitable recesses 54 within the table 2 and are put under tension during this inward movement of the blocks 35, through the medium of plates 53 clamped to the blocks 35 and over the openings of the recesses 54, and between which plates 53 and the inner walls of the recesses 54 said springs 49 are contained.

The foregoing means which have been described in detail effect the assembling of the toe and heel forms and the intermediate steel band, the same being repeated automatically as fast as the complete articles are removed and the parts for a succeeding tree are inserted in the machine, the springs 22 and 49 retrieving the mechanism so that all of the elements are restored to their initial starting position, as will be readily understood. Now, irrespective of the mechanisms for thus assembling the tree elements, I shall describe and have shown in the accompanying drawings, elements for nailing the forms to the intermediate connector so that there is no possibility of the same pulling apart. I have shown this nailing mechanism in connection with the other improved mechanism for assembling the trees which has already been described. This nailing

function is effected by the action of a third pair of cams 37 which act upon rollers 38 secured to rock-levers 39, the outer ends of said levers 39 being secured to the lower ends of vertically-disposed pins 40 whose upper ends are secured to the ends, respectively, of a bar 41 secured to and intersecting a casing 42 which in turn is secured to and intersects a pair of blocks 43 disposed somewhat inwardly of the ends of the bar 41 and carrying depending bars 44 adapted to reciprocate within housings 45 mounted upon blocks 55 secured to the auxiliary table 27 and having feed chutes 46 for nails 47, these chutes being adapted to discharge the nails 47 in vertical alignment with the holes 48 formed in the ends of the steel connector 23. The lower ends of the depending bars 44 lie adjacent the top of the nails 47 as the same are discharged from the chutes 46, so that the downward movement of the bars 44 caused by the movement of the frame 42 when the levers 39 are rocked, will cause said bars 44 to force the nails 47 through the forms 24 and 25 to intersect the holes 48. The nails 47 may be furnished to the chutes 46 either manually or by any suitable automatic feed device, the particular means not forming any part of this invention. The inner ends of the levers 39 rock upon a bar 51 suitably mounted in the frame and coiled upon this bar is a spring 50 whose respective ends lie beneath the inner ends of the levers 39, as plainly shown in Figure 1. It is evident that the downward movement of the inner ends of the levers 39 will put the spring 50 under tension and that the continued rotation of the cams 37 will release the levers 39 and will permit the spring 50 to rock the levers 39 to their initial starting position.

What I claim is:

1. In a machine for making shoe-trees, the combination of power means; means for holding a toe portion of a shoe-tree; means for holding a body portion of a shoe-tree; and means for moving said two sets of holding means relatively to each other so as to cause said body to be inserted in said toe portion.

2. In a machine for making shoe-trees, the combination of power means; means for holding a toe portion of a shoe-tree; means for holding a body portion of a shoe-tree; means for moving said two sets of holding means relatively to each other so as to cause said body portion to be inserted in said toe portion; and means tending to hold the toe portion and body portion holding means normally apart.

3. In a machine for making shoe-trees, the combination of power means; means for holding a toe portion of a shoe-tree; means for holding a body portion of a shoe-tree; means for moving said two sets of holding

means relatively to each other so as to cause said body portion to be inserted in said toe portion; and means adapted to nail said body portion to the toe portion of the shoe-tree.

4. In a machine for making shoe-trees, the combination of power means; means for holding a toe portion of a shoe-tree; means for holding a body portion of a shoe-tree; means for moving said two sets of holding means relatively to each other so as to cause said body portion to be inserted in said toe portion; means furnishing a nail adjacent said toe portion; and means adapted to force 10 the nail into said toe portion to intersect said body portion.

5. In a machine for making shoe-trees, the combination of power means; a shaft rotated thereby; a pair of cams secured to said 20 shaft; a support; holding means for the toe portion of a shoe-tree and receiving means for the body portion of a shoe-tree mounted upon said support; means actuated by one of said cams and adapted rigidly to hold 25 said body portion; and means actuated by the other of said cams to move said toe portion holding means toward one end of said body whereby said body end is inserted in said toe portion.

30 6. In a machine for making shoe-trees, the combination of power means; a shaft rotated thereby; a pair of cams secured to said shaft; a support; holding means for the toe portion of a shoe-tree and receiving means 35 for the body portion of a shoe-tree mounted upon said support; means actuated by one of said cams and adapted rigidly to hold said body portion; means actuated by the other of said cams to move said toe portion holding means toward one end of said body whereby said body end is inserted in said toe portion; means tending to hold said body holding means in their non-clamping position; and means tending to hold the toe portion holding means and the body portion receiving means normally apart.

45 7. In a machine for making shoe-trees, the combination of power means; a shaft rotated thereby; three cams secured to said shaft; a 50 support; holding means for the toe portion of a shoe-tree and receiving means for the body portion of a shoe-tree mounted upon said support; means actuated by one of said cams and adapted rigidly to hold said body portion; means actuated by another of said cams to move said toe portion holding means toward one end of said body portion whereby said body portion end is inserted in said toe portion; and means actuated by the third of said cams and adapted to nail said body portion to the toe portion of the shoe-tree.

60 8. In a machine for making shoe-trees, the combination of power means; a shaft rotated thereby; three cams secured to said shaft; a 55 support; holding means for the toe portion

of a shoe-tree and receiving means for the body portion of a shoe-tree mounted upon said support; means actuated by one of said cams and adapted rigidly to hold said body portion; means actuated by another of said cams to move said toe portion holding means toward one end of said body portion whereby said body portion end is inserted in said toe portion; means actuated by the third of said cams and adapted to nail said body portion to the toe portion of the shoe-tree; and means tending to hold said toe portion holding means and said body portion receiving means normally apart.

65 9. In a machine for making shoe-trees, the combination of power means; a shaft rotated thereby; three cams secured to said shaft; a support; holding means for the toe portion of a shoe-tree and receiving means for the body portion of a shoe-tree mounted upon said support; means actuated by one of said cams and adapted rigidly to hold said body portion; means actuated by another of said cams to move said toe portion holding means toward one end of said body portion whereby said body portion is inserted in said toe portion; means furnishing a nail adjacent said toe portion; and means actuated by the third of said cams and adapted to force the nail into said toe portion to intersect said body portion.

70 10. In a machine for making shoe-trees, the combination of power means, a shaft rotated thereby; three cams secured to said shaft; a support; holding means for the toe portion of a shoe-tree and receiving means for the body portion of a shoe-tree mounted upon said support; means actuated by one of said cams and adapted rigidly to hold said body portion; means actuated by another of said cams and adapted to move said toe portion holding means toward one end of said body portion whereby said body portion is inserted in said toe portions; means furnishing a nail adjacent said toe portion; means actuated by the third of said cams and adapted to force the nail into said toe portion to intersect said body portion; and means tending to hold said toe portion holding means and said body portion receiving means normally apart.

75 11. In a machine for making shoe-trees, the combination of power means; a shaft rotated thereby; three cams secured to said shaft; a support; holding means for the toe portion of a shoe-tree and receiving means for the body of a shoe-tree mounted upon said support; means actuated by one of said cams and adapted rigidly to hold said body portion; means actuated by another of said cams to move said toe portion holding means toward one end of said body portion whereby said body portion is inserted in said toe portion; means actuated by the third of said cams and adapted to nail said

body portion to the toe portion of the shoe-tree; means tending to hold said toe portion holding means and said body portion receiving means normally apart; and a spring 5 tending to hold said nailings means in its initial position.

12. In a machine for making shoe-trees, the combination of power means; a shaft rotated thereby; three cams secured to said 10 shaft; a support; holding means for the toe portion of a shoe-tree and receiving means for the body portion of a shoe-tree mounted upon said support; means actuated by one of said cams and adapted rigidly to hold 15 said body portion; means actuated by another of said cams to move said toe portion holding means toward one end of said body portion whereby said body portion end is inserted in said toe portion; means 20 furnishing a nail adjacent said toe portion; means actuated by the third of said cams and adapted to force the nail into said toe portion to intersect said body portion; and a spring tending to hold said nail forcing 25 means in its initial position.

13. In a machine for making shoe-trees, the combination of power means; means actuated thereby and adapted to force toe and heel portions of a shoe-tree onto an intermediate connector; a shaft rotated by said power means; a pair of cams secured to said shaft; and means actuated by said cams and adapted to nail said connector to said toe and heel portions, respectively.

35 14. In a machine for making shoe-trees, the combination of power means; means actuated thereby and adapted to force the toe and heel portions of a shoe-tree onto an intermediate connector; a shaft rotated by 40 said power means; a pair of cams secured to said shaft; means actuated by said cams and adapted to nail said connector to said toe portion and heel portion, respectively; and means tending to hold said nailings 45 means in their initial position.

15. In a machine for making shoe-trees, the combination of power means; means actuated thereby and adapted to force the toe and heel portions of a shoe-tree onto and 50 over the respective ends of an intermediate connector; a shaft rotated by said power means; a pair of cams secured to said shaft; means furnishing nails adjacent said toe and heel portions, respectively; and means actuated by said cams and adapted to force 55 the nails into said toe portion and said heel portion, respectively, to intersect said connector.

60 16. In a machine for making shoe-trees, the combination of power means, means actuated thereby to force the toe portion and the heel portion of a shoe-tree onto and over the respective ends of an intermediate connector; a shaft rotated by said power means; 65 a pair of cams secured to said shaft; means

furnishing nails adjacent said toe portion and said heel portion, respectively; means actuated by said cams and adapted to force the nails into said toe portion and said heel portion, respectively, to intersect said connector; and a spring tending to hold said nail forcing means in their initial position. 70

17. In a machine for making shoe-trees, the combination of power means; a shaft rotated by said power means; a pair of cams 75 secured to said shaft; shoe-tree holding means, said tree including a toe portion, a heel portion and an intermediate connector; and means actuated by said cams and adapted to force nails into the toe and heel portions, respectively, to intersect said connector. 80

18. In a machine for making shoe-trees, the combination of power means; a shaft rotated by said power means; a pair of 85 cams secured to said shaft; shoe-tree holding means, said tree including a toe portion, a heel portion and an intermediate connector; and means actuated by said cams and adapted to force nails into the toe and heel portions, respectively, to intersect said connector; and means tending to hold said nail-forcing means in their initial position. 90

19. In a machine for making shoe-trees, the combination of power means; a shaft rotated by said power means; a pair of cams 95 secured to said shaft; shoe-tree holding means, said tree including a toe portion, a heel portion and an intermediate connector; means furnishing nails adjacent said toe and heel portions, respectively; and means actuated by said cams and adapted to force 100 nails into said toe and heel portions, respectively, to intersect said connector.

20. In a machine for making shoe-trees, the combination of power means; a shaft rotated by said power means; a pair of cams secured to said shaft; shoe-tree holding means, said tree including a toe portion, a heel portion and an intermediate connector; means furnishing nails adjacent said toe and heel portions, respectively; means actuated by said cams and adapted to force 105 nails into said toe and heel portions, respectively, to intersect said connector; and a spring tending to hold said nail-forcing means in their initial position. 110

21. In a machine for making shoe-trees, the combination of power means; means for holding a toe portion of a shoe-tree; means for holding a heel portion of a shoe-tree; means for holding a connector adapted to extend between the toe and heel portions of a shoe-tree; and means for moving the toe portion and heel portion holding means relative to each other and the connector so as to cause said connector to be inserted in 115 said toe and heel portions. 120

22. In a machine for making shoe-trees, the combination of power means; means for 125

holding a toe portion of a shoe-tree; means for holding a heel portion of a shoe-tree; means for holding a connector adapted to extend between the toe and heel portions of a shoe-tree; means for moving the toe portion and heel portion holding means relative to each other and the connector so as to cause said connector to be inserted in said toe and heel portions; and means tending to hold the toe portion and heel portion holding means normally apart.

23. In a machine for making shoe-trees, the combination of power means; means for

holding a toe portion of a shoe-tree; means for holding a heel portion of a shoe-tree; means for holding a connector adapted to extend between the toe and heel portions of a shoe-tree; means for moving the toe portion and heel portion holding means relative to each other and the connector so as to cause said connector to be inserted in said toe and heel portions; and means adapted to nail said connector to the toe and heel portions of the shoe-tree.

Signed by me this 1st day of June, 1923.
LOUIS F. VOISARD.
